(57) **CLAIM**

The ornamental design for a skid frame, as shown and described.

DESCRIPTION

FIG. 1 is a front perspective view of a skid frame showing our new design;

FIG. 2 is a rear perspective view of the design for the skid frame of FIG. 1;

FIG. 3 is a front view of the design for the skid frame of FIG. 1;

FIG. 4 is a rear view of the design for the skid frame of FIG. 1;

FIG. 5 is a left side view of the design for the skid frame of FIG. 1;

FIG. 6 is a right side view of the design for the skid frame of FIG. 1;

FIG. 7 is a top view of the design for the skid frame of FIG. 1; and,

FIG. 8 is a bottom view of the design for the skid frame of FIG. 1.

The broken lines in the figures show portions of the skid frame which form no part of the claimed design.
